United States Patent Office

Des. 187,731
Patented Apr. 26, 1960

187,731

MOTOR TRUCK

Evan S. Prichard, La Canada, Calif., assignor to Cook Bros. Equipment Co., Los Angeles, Calif., a corporation of California

Application May 4, 1959, Serial No. 55,773

Term of patent 14 years

(Cl. D14—3)

FIG. 1.

FIG. 2.

FIG. 3.

FIG. 4.

The essential features of my design reside in those portions shown in full lines.

I claim:

The ornamental design for a motor truck, as shown and described.
